ABSTRACT

A plurality of tumblers are rotated by means made operable by selective movements of a combination dial to place conductive or dielectric peripheral regions of the tumblers in circuit making or breaking contact with spring contact fingers. The tumblers comprise annular outer portions surrounding inner portions which are independently rotatably mounted on a shaft. Releasable lock members normally connect the two tumbler portions together for conjoint rotation. A pin is insertable from the rear of the switch through openings in the outer tumbler portions to both move the lock member into release positions and lock such outer portions together. This permits use of the dial to change the azimuthal position of the peripheral segments relative to the dial indicia to change the combination of the switch.

The spring fingers are portions of a circuit board which also includes conductors leading from the fingers to terminals. The circuit board is made flat and is then folded and installed into openings for same formed in a dielectric support member.

PERMUTATION SWITCH

CROSS-REFERENCES TO RELATED APPLICATIONS

This application is a continuation-in-part of my copending application Serial No. 29,528, filed April 17, 1970, and entitled Permutation Switch.

BACKGROUND OF THE INVENTION

1. Field of the Invention

This invention relates to improvements in permutation switches of the general type shown and described in: U.S. Pat. No. 2,797,271, granted June 25, 1957 to Arthur L. Augustine; U.S. Pat. No. 2,984,717, granted May 16, 1961 to Raymond W. Davidson and U.S. Pat. No. 3,192,331, granted June 29, 1965 to Raymond W. Davidson.

2. Description of the Prior Art

Each of the aforementioned U.S. Pat. Nos. 2,797,271; 2,984,717 and 3,192,331 shows a permutation switch of the general type to which the present invention relates. In a switch of this type a plurality of disc-like tumblers are arranged for free selective rotation about a support shaft mounted in a case. The tumbler peripheries have conductor and insulator regions. Contact brushes or fingers are mounted on the inside of a lateral wall of the case and project radially inwardly into contact with the peripheries of the tumblers. A combination dial is secured to one end of the shaft and a radial arm is secured to the opposite end. This radial arm and some rotary motion transmitting abutments on the tumblers function upon selective movements of the dial to temporarily couple the tumblers to the shaft, so that further shaft movement causes tumbler movement.

In the permutation switches disclosed by these three patents multi-position connections are provided between the shaft and the actuator arm so that the operating combination of the switch can be changed by a simple change in the azimuthal position of the actuator arm relative to the shaft. Also, U.S. Pat. No. 3,192,331 discloses a multi-position connection between the operating dial and the shaft, permitting further changes in the operating combination. As can be readily appreciated, in these prior art switches the number of combination changes achievable is a limited number, dependent upon the possible number of different azimuthal position settings of the actuator arm and/or operating dial relative to the shaft. Also, assembly and disassembly of the internal switch parts is a problem. This is because the contact fingers are leaf springs and must be held out of engagement with the tumblers during installation and removal of the contact fingers and their support from the switch housing. If not done properly, the contact fingers can be distorted out of shape, broken, or both.

Permutation switch tumblers having inner and outer parts which are movable relative to each other for the purpose of changing the switch combination are disclosed by the following U.S. Pat: No. 389,703, granted Sept. 18, 1888 to Charles Hill; U.S. Pat. No. 1,381,409 granted June 14, 1921 to J. A. Freeze; U.S. Pat. No. 1,469,651 granted Oct. 2, 1923 to L. F. Hymel; U.S. Pat. No. 1,670,448 granted May 22, 1928 to Frank Hanna; U.S. Pat. No. 1,725,086 granted Aug. 20, 1929 to E.V. Larson; U.S. Pat. No. 1,744,707 granted Jan. 21, 1930 to S. de Castro E Iznaga; U.S. Pat. No.

3,237,435 granted Mar. 1, 1966 to George D. Paul and U.S. Pat. No. 3,254,519 granted June 7, 1966 to George D. Paul. However, none of these patents discloses a switch in which the inner and outer tumbler parts are unlocked by a pin which is inserted through an opening in the back of the switch and then axially through all of the outer tumbler portions, so that a new combination may be dialed.

10 SUMMARY OF THE INVENTION

A principal object of the present invention is to provide multi-position connections between the conductive or dielectric region carrying portions of the tumblers and the dial controlled tumbler rotating elements, for the purpose of providing an almost infinite number of combination settings.

According to the invention, each tumbler comprises an inner portion which is freely rotatable about the support shaft, and an annular outer portion which concentrically surrounds the inner portion. The outer portion carries the make or break regions of the tumblers. A releasable lock means normally connects the two tumbler portions together for conjoint rotation. When the lock means are released the inner tumbler portions are rotatable relative to the outer tumbler portions.

In the preferred embodiment of the present invention, the lock means are arranged so that they can all be simultaneously moved into their release positions by an elongated pin inserted from the rear of the switch through aligned openings in the outer portions of the tumbler. The pin serves to both release the lock means and to secure together the outer portions of the tumblers. In operation, the dial is turned in accordance with the existing combination of the switch to place the conductive or dielectric regions of the tumblers in a circuit making or breaking position relative to the contact brushes or fingers. The pin element is then inserted through the tumbler outer portions for the purpose of releasing the lock means and also holding the outer tumbler portions together and the conductive or dielectric segments thereof aligned. Next, the dial is manipulated for the purpose of changing the relative azimuthal positions of the inner tumbler portions, and the tumbler rotation causing elements thereon, relative to the outer tumbler portions and the conductive or dielectric regions thereon. This manipulation also serves to change the relative azimuthal positions of the conductive or dielectric regions relative to the indicia on the dial. The pin is then removed, permitting automatic return of the lock means to their lock positions. This readies the switch for further operation by use of the new combination.

55 Another principal feature of the present invention is the provision of a novel inner casing and electrical contact finger assembly construction which facilitates manufacturing and assembly of the switches. According to the invention, each switch is provided with a longitudinally split inner casing of a dielectric material. Each casing part is adapted to be radially joined with the other part to form a cylindrical casing. Each part includes an axial recess formed in its outer surface for receiving a folded portion of a circuit board, and side windows in the recess for accommodating contact finger portions of the circuit board. A generally radial slot is provided in a radial end wall of each part to

receive an unfolded portion of the circuit board. A second folded portion of the circuit board is folded around against the back side of said radial wall. Support shelves for the opposite ends of the contact fingers are provided at the region of the windows and also laterally across the inner casing part.

The circuit board provides the contact fingers which ride on the peripheries of the tumblers and the conductors leading from such fingers to terminals at which wires are connected to the switch. The circuit boards are initially formed in a flat condition. The conductive areas may be formed by printing, depositing, or by otherwise providing conductive strips or areas on a nonconductive base member or substrate. Then the circuit board is folded into a particular configuration for insertion into the recess, windows, slots and other regions formed for them in the casing inner parts. The inner casing parts are moved radially into engagement with the tumbler set. The spring contact fingers deflect and apply an inward force on the tumblers when the casing parts are in place. The assemblage of the casing parts and the tumbler set is then slid axially into an outer switch casing. At no time do the contact fingers have to be sprung radially outwardly by a tool so that either they or the tumbler set can be installed or removed.

The present invention also relates to certain specific and particularly advantageous constructions of the tumblers, and to other features and arrangements which are exemplified by the embodiments hereinafter described.

BRIEF DESCRIPTION OF THE DRAWING

FIG. 1 is an axial sectional view of an embodiment of the invention, with some internal parts shown in side elevation;

FIG. 2 is an exploded isometric view of the embodiment;

FIG. 3 is a cross-sectional view taken substantially along line 3—3 of FIG. 1;

FIG. 4 is a rear elevational view taken from the aspect denoted by line 4—4 in FIG. 1;

FIG. 5 is an exploded isometric view of one of the tumblers, looking towards the side of the tumbler on which the locking member is located;

FIG. 6 is an assembled isometric view of the tumbler taken from substantially the SAME aspect as FIG. 5;

FIG. 7 is an assembled isometric view of the tumbler taken from an aspect looking towards the opposite side of the tumbler;

FIG. 8 is a side elevational view of the tumbler, taken from an aspect looking towards the same side of the tumbler that is the front side in FIG. 7;

FIG. 9 is an axial sectional view taken through the tumbler substantially along line 9—9 of FIG. 8;

FIG. 10 is a side elevational view of the tumbler looking towards the side of the tumbler on which the locking member is situated;

FIG. 11 is an axial sectional view taken substantially along line 11—11 of FIG. 10;

FIG. 12 is a top plan view of an electrical contact finger-lead wire circuit board;

FIG. 13 is an isometric view of the circuit board showing it shaped for use;

FIG. 14 is a fragmentary top plan view of a modified circuit board, usable in a normally open switch; and

FIG. 15 is a fragmentary top plan view of still another modified form of circuit board, formed to include a third conductor.

DESCRIPTION OF THE PREFERRED EMBODIMENT

The present invention relates to both normally open and normally closed switches. By way of typical and therefore nonlimitative example, the invention is illustrated and will now be described in connection with a normally open switch.

Referring to FIG. 1, the switch 10 is shown to comprise a casing having a cylindrical side wall 12, an integral front wall 14 and a removable rear cover plate 16.

A tumbler-supporting and operating shaft 18 is journaled, such as by a journal 20, within an opening provided in the front wall 14. Shaft 18 is shown to have a non-circular (e.g. square) cross-sectional portion 22 at its forward end which snugly fits within a socket of similar shape formed in a concealed control knob 24, and secured by a laterally extending set screw 26. A conical entrance way 28 is formed in the forward portion of control knob 24. The side walls of entrance way 28 slope radially inwardly towards a noncircular socket 30 for receiving a similarly shaped inner end portion 32 of a combination dial 34. The switch 10 and the control knob 24 may be secured inside of a cabinet or behind a wall or barrier 35 (FIG. 2), with access to it consisting only of a relatively small opening in the wall portion of the cabinet, or in the barrier 35, which opening is coaxially aligned with the socket 30, for receiving the inner end portion 32 of the control dial 34.

As shown best by FIGS. 1 and 5—11, each tumbler T is in the form of a two part circular disc or wheel. The inner part 36 has an axial opening 38 therein sized for receiving a tubular bushing 40 which surrounds the shaft 18. The annular outer tumbler portion 42 includes a central axial opening 44 for receiving an axial extension 46 of the inner tumbler portion 36. Lock mechanisms, hereinafter to be described in detail, normally connect the two tumbler portions together for conjoint rotation.

A radial actuator arm 48 (FIG. 1) is secured in a fixed position to the rear end portion of the shaft 18. This arm 48 includes a noncircular opening at its mounted end in which is received a complementary shaped rear end portion of the shaft A a cotter pin 50 may extend through the rear end portion of shaft 18 for the purpose of holding the arm 48 and the tumblers T on the shaft surrounding sleeve 40. Arm 48 also includes a forwardly directed axial pin or abutment 51 which rides in a circular channel 54 formed in the rear side of the inner tumbler portion 36.

An axially extending driving pin 52 (FIG. 7, for example) extends forwardly from each tumbler inner portion 36. A radially extending driving abutment 56 (FIG. 10, for example) is provided on the rear side of each inner tumbler portion 36. The driving pin 52 of each tumbler T travels a collision path with the abutment 56 of the tumbler immediately forwardly of it. The driving web 56 of the rear tumbler T is positioned to be in the rotational path of the forwardly projecting pin 51 on arm 48.

The periphery of each tumbler T is provided with adjoining V notches, some of which are designated 58,

defining between them transverse ridges or lands of triangular section. Each outer tumbler portion 42 is made from plastic or some other dielectric material and a region of its periphery is recessed at 60 (FIG. 5, for example) to receive a segment 62 of a conductive material.

As best shown by FIG. 2, a longitudinally split inner casing or housing, composed of complementary parts 64, 66 is received within the casing 12, 14. These members 64, 66 are made from a dielectric material (e.g. plastic) and serve to retain and properly position a pair of folded circuit board members 68, 70.

Reference is now made to FIGS. 12 and 13, depicting a circuit board 68. In FIG. 12 the board 68 is shown in its flat condition. It is shown to include a base member 72 of plastic, plasticized paper, etc. which is dielectric in nature. Conductive lead lines or paths 74, 76 are printed, deposited, or otherwise emplaced on the member 62. Also, an insulative layer or laminate may be placed over the conductive paths 74, 76 to provide an insulative cover therefor. One end of each conductive path 74, 76 is connected to a flat, apertured terminal member 78, 80. The opposite ends of the conductive paths 74, 76 connect to initially flat, outside located conductor members or fingers 82, 84.

The flat circuit boards 68, 70 are suitably folded and creased into the configuration shown by FIG. 13, for example. A portion 86 of each board 68, at the base of the contact fingers 82, 84, is folded as pictured and is placed within an axially elongated, generally radial recess 88 formed in the housing member 64, 66. The contact fingers project chordwise of the housing member 64, 66, through windows provided for them in the side wall of recess 88. Some of these windows are designated 90. A straight flat portion 92 of the circuit board 68, 70 is located within a slot 94 formed in the end wall of the recess 88. A folded terminal carrying portion 96 of the circuit board 68, 70 is disposed rearwardly of the cover member 16, with the terminal end portions 78, 80 fitting within recesses formed therefor and are secured to the member 16 by means of clamp screws 98, 100.

The just described construction of the contact fingers 82, 84 and the lead conductors 74, 76 therefor can be mass produced economically and they, together with the split construction of the inner housing 64, 66 provide for an easy assembly of the internal working components of the switch 10. The folded circuit boards 68, 70 are fitted onto the inner housing parts 64, 66. As shown by FIG. 3, the free ends of the contact fingers 82, 84 rest on a shelf 102 which is substantially in coplanar parallelism with the similar shelf 104 at the base of the windows 90. The straight flat portions 92 of the circuit board member 68, 70 are positioned within additional slots 108 in rear cover member 16 which are alignable with the slots 94. After the folded circuit boards 68, 70 are properly assembled the inner housing parts 64, 66 are brought radially together on opposite sides of the tumbler set 106 (FIG. 2). The tumbler set comprises the tumblers T and the sleeve 40. Next, the assemblage of the inner housing parts 64, 66, the folded circuit board 68, 70, the tumbler set 106 and cover 16 is slid endwise relatively into the outer casing 12, 14. Screw fasteners 110 are inserted through openings 112 provided in the rear cover 16 and are threaded into interiorly tapped sockets formed in inner boss portions

114 which are integral with the side wall 12 of the casing 12, 14. The fasteners 110 secure the cover member to the casing 12, 14 and indirectly hold the assembled internal components of the switch in proper position within the casing 12, 14.

Each set of contact fingers 82, 84 (i.e. each folded circuit board 68, 70) forms with the set of tumblers T an independent switch. A simple variation which would further increase the number of circuits of which the switch 10 may be a part would be to provide a separate lead-in wire 75 (FIG. 15) for the rearmost paired contact fingers 82, 84. Then when the conductive segments 62 of the third and fourth tumblers T are brought into contact with the rearmost paired contact fingers 82, 84 a third circuit will be formed between conductor 74 and the third conductor 75. The terminal 79 for the third conductor could be located between terminal 78, 80. In FIG. 4, the rear cover 16 is shown to include a clamp screw 116 and a socket for the third terminal associated with each circuit board 68, 70.

As shown by FIG. 1, two adjacent contact fingers 82, 84 ride on the serrated or grooved periphery of each tumbler T. As will be apparent, when the conductive segments 62 are aligned and are in contact with the fingers 82, 84, a series circuit is completed from one conductor 74 through such fingers 82, 84 and the segment 62 to the other conductor 76.

In a normally open switch the dielectric and conductive regions of the tumbler peripheries are reversed and the contact finger end of conductor 74 includes a separate branch leading down to each contact finger 82, the contact finger end of conductor 76 includes a branch leading down to each contact finger 84 (FIG. 14). A layer or ply of an insulative material is sandwiched between the two sets of branches. A series circuit is established from each finger 82 through its tumbler T to the contact finger 84 in contact with the same tumbler T. This occurs whenever a pair of associated contact fingers 82, 84 are in contact with the conductive region of their tumbler T. The circuit of which the conductors 74, 76 are a part stays closed until all fingers 82, 84 are in contact with a dielectric region of a tumbler T.

The contact fingers 82, 84 in the illustrated embodiment, and the contact fingers in the non-illustrated normally closed switch embodiment, are spring members and contain sufficient spring energy to normally urge their central portions relatively tightly against the periphery of the tumblers T. Preferably, the central portions of the contact fingers 82, 84 are inwardly bent so as to form a projection which closely fits with the V grooves or valleys 58 (FIG. 3).

From the foregoing, it will be readily apparent that an electrical circuit through the contact finger elements will remain open as long as any two of the contact fingers riding a tumbler T are in contact with a dielectric portion of such tumbler T. In the normally open switch the electrical circuit through the conductors 74, 76 will remain closed as long as a single pair of the fingers 82, 84 are in contact with the conductive region of the tumbler T with which they are in contact. The making or breaking of the electrical circuit in either the normally open switch or the normally closed switch can only be accomplished by rotating the tumblers T relative to each other about their supporting

shaft means 18, 40, by means of the dialing knob 34, and then only by an authorized person who has knowledge of the number of turns to the right or left thereof to bring the various conductive or dielectric minor regions of the tumbler peripheries into contact with the contact fingers.

Initially, the knob 34, and hence shaft 18 and actuator arm 48, will be rotated several revolutions, so as to bring the driving pins 51, 52, beginning with the arm 48, into engagement with the driving webs or abutments 56 of the adjacent tumblers T so that the successive tumblers T will in turn be "picked up" and be rotated along with the arm 48. The first stop at the indicator mark 120 (FIG. 2) will result in the conductive segment 62 of the front tumbler T being brought into engagement with its respective contact fingers 82, 84, thus initially establishing a current path through these two contact fingers and the forward conductive segment 62 alone.

With the front or first tumbler T now held against rotation (by the contoured center region of the contact fingers 82, 84 engagement with the V notches 58 in the conductive segment 62), the knob 34 is rotated in the opposite direction. This causes the driving pin 51 on the actuator arm 48 to first disengage itself from one side of the driving web 56 of the rear tumbler, and to then rotate around into engagement with the other side of said web 56, causing driving pin 52 of the rear or fourth tumbler T to pick up the web 56 of the third tumbler T immediately forwardly thereof, to rotate the same in said opposite direction. Pin 52 of the third tumbler T will pick up the web 56 of the second tumbler T, to rotate the same until its conductive segment 62 is engaged by the tips of its respective contact fingers 82, 84, and held against further rotation thereby. With the first and second tumblers now in the positions just mentioned, the circuit path has been extended to also include the conductive region 62 of the second tumbler T and the two contact fingers 82, 84 in contact therewith. Additional rotation of the dial 34 and the actuator arm 48 in the original direction of rotation will similarly impart rotation to the third tumbler T to position its conductive segment 62 and the associated contact fingers 82, 84 in a contact making position. Further rotation of dial 34 and actuator arm 48 in the reverse direction will finally position the conductive segment 62 of the rear tumbler T into circuit making engagement with its two contact fingers 82, 84, thus completely the series circuit through the contact fingers 82, 84 and the conductive segment 62.

All of the dialing operations described, to be effective, must be done in accordance with the numerical combinations assigned to the switch in its entirety. According to the present invention the tumblers T are constructed so that they can be used to quickly and conveniently vary the relative azimuthal positions of the pins and webs 52, 56 relative to the dial indicia to establish almost an indefinite number of different combinations. A preferred embodiment of the tumbler construction making the large number of combination changes possible will now be described.

As best shown by FIGS. 9 and 11, the rear side of each outer tumbler portion 42 is recessed to receive a greater portion of the inner tumbler portion 36. The forward side of each outer tumbler portion 42 is

recessed at 120, immediately bordering the central opening 42, to form a one sided annular groove or rabbet that is slightly larger in diameter than the central opening 44. The axial extension 46 of the inner tumbler portion 36 includes a radial flange or annulet 122 which is fittable into the rabbet 120. The forward portion of the annulet 122 is beveled so that the inner tumbler portion 36 can be snapped fitted into the outer tumbler portion 42.

When the two tumbler portions 36, 42 assemble, and the annulet 122 is received in the rabbet 120 (FIG. 9) the fit between the two tumbler portions 36, 42 is a relatively loose one, so that the two portions 36, 42 can be rather easily rotated, one relative to the other.

The lock means provided for normally connecting the inner and outer tumbler portions 36, 42 together for conjoint rotation includes a radially movable lock member 124. As best shown by FIGS. 5 and 11, the outer tumbler portion 42 is formed to include a radial slideway 126 in which the lock member 124 is received. The slideway 126 is defined in part by a pair of wings 128, 130 which serve to retain the member 124 in the slideway 126 in the axial direction. The fit between the lock member 124 and the slideway 126 is loose enough to permit the member 124 to move easily in the radial direction.

The inwardly directed end portion of member 124 is serrated or otherwise patterned and the peripheral surface of the inner tumbler portion 36 is complementarily patterned at 134.

A circumferential groove 136 is formed in the member 42 radially outwardly from the slideway 126. This groove 136 has a continuous outer radial boundary and includes inner radial restraining or boundary means 138, 140 only at its ends. The intermediate portion of the spring seat 136 is unrestrained or bounded in the radially inward direction. A normally inwardly biased leaf spring 142 is fitted within the spring seat 136. It includes an intermediate portion which rests on the lock member 124 and serves to bias it radially inwardly, causing its serrations 132 to mate with the serrations 134 on the inner tumbler part 136.

A release pin receiving opening 144 is provided axially through the radial wall portion 146 of each tumbler outer portion 42 in a region which is normally at least partially covered by a midportion of the lock member 124. The angle X (FIG. 8) between the center of opening 144 and the center of the conductive segment 62 is the same for each tumbler T. Thus, when the conductive segment 62 (or the dielectric segments in the normally closed form of switch) are aligned with each other, the openings 144 are also axially aligned with each other and with an opening 148 in the rear cover (FIG. 2).

An axial opening 150 is provided through each lock member 124. Each opening 150 is surrounded by a camming surface 152. The leaf spring 142 normally urges the member 124 into a position in which its opening 150 is positioned slightly radially inwardly of the corresponding opening 144, and the radially outer portion of the cam surface 152 is generally aligned with the openings 144.

According to the present invention, the combination of a given switch 10 is simply and quickly changed by a person dialing the existing combination to place the

segment 62 in line and the openings 144 in alignment with each other and with the rear cover opening 148. Then an elongated pin 154 is inserted successively first through the opening 148 and then the openings 144 in the respective outer tumbler portions 42. Wall means 149 may be provided to make opening 148 be an elongated guide passageway for the pin 154.

Since entrance into the openings 144 is partially blocked by the lock members 124, the pin 154 must first move the lock levers 124 out of the way. The sloping cam surface 152 serves to facilitate this movement. The force of the pin 154 on the incline set cam surface 152 causes an outward sliding movement of the lock member 124 within its slideway 126 against the resistance of the leaf spring 142. When pin 154 is situated within the openings 144 it serves to hold the patterned end portions 132 of the lock members 124 radially outwardly from a position of locking engagement with the patterned peripheries 134 of the inner tumbler portions 136. It also serves to lock together the outer tumbler portions 42 and hold them in a constant position with respect to the contact fingers 82, 84. The operator then manipulates the dial 34 to reset the combination. Rotation of the dial 34 and the shaft 18 causes rotational movement of the tumbler inner portions 36 via the arm 44, its pin 51, the pins 52 and the abutments 56. Once a new combination is established the pin 154 is removed, resulting in a return of the lock members 124 to locking positions. Thereafter the switch is operable by the new combination.

According to the invention, a second spring seat 156 is located diametrically across the tumbler outer portion 42 from spring seat 136. It is of similar construction, having means at its two ends for holding a second leaf spring 158. This second leaf spring 158 is biased radially inwardly and rests on the pattern periphery 134 of the tumbler inner portion 36. Its function is to retard relative rotation between the two tumbler parts 36, 42, so that rotation will not occur unless it is positively caused by a rotation of the inner tumbler portion 36 relative to the outer tumbler portion 42. In this respect it has the same rotational retarding effect as the contact fingers 82, 84 on the tumblers T in their entireties.

Obviously, many modifications and variations of the present invention are possible in light of the above teachings. It is therefore to be understood that within the scope of the appended claims, the invention can be practiced otherwise than as specifically described.

What is claimed is:

1. A permutation switch tumbler comprising an inner portion which in use rotates about a central support; an annular outer portion surrounding said inner portion, said outer portion having conductive and dielectric regions; and a radially movable releasable lock member carried by one of said portions, said lock member being movable radially between a lock position wherein it makes locking engagement with the other portion and the two portions are locked together for conjoint rotation, and a release position wherein it is free of engagement with said other portion and the two tumbler portions are rotatable relative to each other, said lock member including an oblique side located cam surface oriented such that a generally axial inward force against said surface will cause a radial sliding movement of the locking lever from its lock position into its release position.

2. A permutation switch tumbler according to claim 1, wherein said inner portion has a patterned periphery, said lock member is carried by said outer portion and has a patterned end portion directed towards said periphery, and said tumbler further includes spring means normally urging said releasable lock member towards the inner portion and its patterned free end portion against the patterned periphery of said inner portion.
3. A permutation switch tumbler according to claim 2, further including second spring means anchored on said outer portion and exerting a drag force on said inner portion when the two portions are not locked together.
4. A permutation switch tumbler according to claim 1 wherein said outer portion comprises a radially directed slideway for receiving the lock member, and a circumferentially extending leaf spring retaining recess positioned radially outwardly of said slideway, wherein said lock member is slidably received in said slideway, and wherein a spring is contained within said spring recess, said spring serving to normally urge the lock member radially inwardly toward the inner portion of the tumbler.
5. A permutation switch tumbler according to claim 4, wherein said spring means is a leaf spring and said spring recess includes means holding the end portions of said leaf spring, with an intermediate portion of said spring being bowed and in force applying contact with said lock member.
6. In a permutation switch of a type comprising a plurality of coaxial, independently rotatable, generally cylindrical tumblers, each of which has conductive and dielectric peripheral regions, conductor elements resting on the periphery of each tumbler, a tumbler control member, and means associated with said tumblers and operable upon selective rotation of said tumbler control member for rotating said tumblers into positions wherein the conductive segments are in circuit-making contact with the conductor elements or the dielectric regions are in circuit-breaking contact with the conductor elements, the improvement comprising: said conductor elements comprising a plurality of spring fingers, and said switch including a circuit board to which end portions of said fingers are secured, electric conductor strips on said circuit board extending from at least some of said fingers, each to a terminal, said tumblers being at least partially surrounded by a dielectric support member formed to engage portions of said circuit board and hold said fingers in position to contact said tumblers.
7. The permutation switch improvement of claim 6, wherein said dielectric support member includes a recess for receiving a portion of the circuit board which is situated adjacent where the spring fingers connect to the circuit board.
8. The permutation switch improvement of claim 6, wherein said support member includes means for supporting the opposite ends of the spring fingers, said spring fingers being unrestrained between their ends and each including an intermediate portion which is in contact with the periphery of one of the tumblers.
9. The permutation switch improvement of claim 6, further including a wall portion formed to include terminal stations, with said circuit board including a portion extending to said terminal stations and serving to place the said terminals at said terminal stations.

10. The permutation switch improvement of claim 9, wherein said wall portion is a radial wall spaced rearwardly of said tumblers, said radial wall includes a slot for receiving a portion of the circuit board, and a terminal end portion of the circuit board is on the opposite side of said wall from said tumblers and is folded back against said radial wall.

11. The permutation switch improvement of claim 6, wherein said dielectric support member is in part at least a segment of a cylinder, said member includes an axially extending recess formed in an outer portion thereof which is sized to receive a portion of the circuit board which is situated immediately inwardly of where the spring fingers connect to the circuit board.

12. The permutation switch improvement of claim 11, wherein said circuit board is folded back on itself at

least once in the region thereof which is received in said recess.

13. The permutation switch improvement of claim 11, wherein said support member includes means for supporting the opposite ends of the spring fingers, said spring fingers being unrestrained between their ends and each including an intermediate portion which is in contact with the periphery of one of the tumblers.

14. The permutation switch improvement of claim 12, wherein said support member includes means for supporting the opposite ends of the spring fingers, said spring fingers being unrestrained between their ends and each including an intermediate portion which is in contact with the periphery of one of the tumblers.
